UNITED STATES PATENT OFFICE

HJALMAR NORDVALL, OF CHICAGO, ILLINOIS.

GRINDING-MACHINE.

1,130,011.

Specification of Letters Patent.

Patented Mar. 2, 1915.

Application filed March 24, 1913. Serial No. 756,296.

To all whom it may concern:

Be it known that I, HJALMAR NORDVALL, a subject of the King of Sweden, and a resident of Chicago, Cook county, Illinois, have invented certain new and useful Improvements in Grinding-Machines, of which the following is a specification.

My invention relates to combination machines and has particular reference to a machine for home use that embodies a plurality of utilities. In general the machine consists of the combination with a vise adjustable to a bench, of a grinding wheel adjustably mounted over the vise-jaws so that the latter may be utilized to firmly hold work which needs to be held in a vise, and provided with a tilting table which may be temporarily mounted on the vise; as in the case of the grinding wheel, to hold other kinds of work in proper relation to the grinding wheel. Foot power air-pressure is utilized as the driving force and the exhaust air is directed to clear the work of dust.

In the accompanying drawing Figure 1 is a side elevation, partly in section, of a machine embodying my invention. Fig. 2 is a plan view of the machine. Fig. 3 is a perspective view on a small scale of the machine equipped with driving means. Fig. 4 is a section taken substantially on line 4—4 of Fig. 1. Fig. 5 is a sectional elevation of the motor, taken substantially on line 5—5 of Fig. 2. Fig. 6 is a section taken substantially on line 6—6 of Fig. 2.

In the several views 2 represents a conventional vise secured by a clamp 3 to a bench 4 and provided with an anvil portion 5 and jaws 6 and 7 the latter being movable on a pivot 8. On the jaw 7 is a lug 9 which has a threaded horizontal bore that is engaged by a screw 10 turned by means of a hand-wheel 11. The ends of the screw are journaled in bearings 12 at the ends of a work-table 13, near its upper edge. Near its lower edge the table 13 is supported by a curved leg 14 which is slidably mounted on a rod 15 having its ends secured to brackets 16 near the ends and lower edge of the table, said leg being mounted at one end for sliding movement in a slot 17 in the body of the vise. The leg is normally held against sliding movement in this slot by a bolt 18 with a winged head 19, this bolt engaging a threaded bore in the vise and its inner end bearing against the leg

14. Immediately back of the jaw 6 the body of the vise has thereon a T-shaped lug or support 20 which engages a correspondingly formed slot 21 in the lower end 60 of a standard 22 which is hollow and is telescoped by a vertically adjustable support 23 on the upper end of which is fulcrumed on a bolt 24 a lever 25. The bolt 24 engages a slot 26 in the lever whereby the latter is longitudinally adjustable on the bolt.

The handle-end 27 of the lever is held normally raised by a spring 28 having its upper end secured at 29 to the rear end of the 70 lever and its lower end secured to a lug 30 on the standard 22. The latter is removably secured to the lug 20 by means of a set screw 31 while the vertically adjustable member 23 is held in its adjusted position by a set screw 75 32 having threaded engagement with the standard 22 and bearing against the member 23. The bolt 24 has a wing nut 33 to facilitate its removal by hand to release the lever 25 from its fulcrum. The spring 28 has 80 hook ends which may be quickly released from the apertures in the lever and the lug 30, as shown. On the lever 25 is a bearing 34 for a rotary shaft 35 having keyed to one end thereof an air-motor 36. On the opposite end of this shaft is a ball-joint ball 37 to which is fitted a hub for a grinding wheel consisting of a pair of clamp-members 38 and 39 secured together by screws 40 and 41 passing through bores in the member 38 and 90 having threaded engagement with the member 39, as shown in Fig. 6. In the periphery of the hub is a groove 42 in which is secured an annular grinding wheel 43. The hub and its wheel 43 are angularly adjustable relative to the shaft 35 on the ball-joint for which purpose the latter has therein a slot 44 loosely engaged by the inner end of a screw 45 that has threaded engagement with the member 38 of the hub. The angular adjustment is effected by a fork having fork-members 46 and 47 that engage opposite sides of the hub as in Fig. 4. This fork is provided with a shank 48 that is engaged with a horizontal slot 49 in a standard 95 50 that rises from the bearing 34. The shank 48 is movable longitudinally in the slot 49 whereby the wheel 43 is tilted to accommodate it to various angles of surface that the grinding wheel is caused to operate upon. 100 The shank is held in any position into which it has been adjusted by a set screw 51 having

105 110

threaded engagement with a bore in the standard and bearing against the shank. The inlet to the air-motor which is on the same shaft as the grinding wheel, is at 53 5 and the outlet is at 52. The inlet is connected by means of a flexible tube 54 with an air-pressure tank 55 (Fig. 3) into which air is pumped by a compressor or engine 56 which may be driven by a treadle 57 pivoted 10 at 58 to a stationary part of the engine and pivoted at 59 to a crank connection with a fly wheel 60, the details of which are immaterial, as any other mechanism for the purpose adapted to accomplish it will serve just 15 as well for the purpose of the present invention. The outlet, or exhaust, of the air-engine 36 is provided with a nozzle 61 which is arranged to direct the outflowing exhaust air against the work and the grinding wheel. 20 62 represents a saw on the tilting table arranged to have its teeth ground or sharpened by the tapered type of grinding wheel shown. 25 63 and 64 are clamps for holding the work when this is of such a nature that it requires the support of the table 13 with or without its clamps. The opening between the vise jaws, together with the adjustability of the grinding-wheel and its engine, is adapted to 30 take the place of the table as work-holding means where a vise-hold is needed. At the exhaust or air-outlet for the engine 36 is arranged a valve 65 controlled by a finger le-

ver 66 connected with the valve 65 by a rod 67. By means of this lever and valve the operator may stop and start the engine by stopping and starting the flow therethrough of the air. 35

It will be noticed that the grinding machine attachments are quickly removable 40 from the vise when it is desired to use the latter exclusively as a vise and not as a mere support and work-holder for the grinder. 45

Having thus described my invention, I claim as new and desire to secure by Letters Patent—

1. The combination with an angularly and longitudinally adjustable hand-lever, of a grinding wheel and the like rotary element operative upon a piece of work, means for 50 rotating same, and means on said lever for controlling the motive power.

2. The combination with a hand-lever, of means for adjusting said lever vertically and horizontally with respect to its axis of angular movement, a source of power, a driving motor on said lever, and means on said lever for controlling said motor. 55

In testimony whereof I have hereunto set my hand in the presence of two subscribing 60 witnesses.

HJALMAR NORDVALL.
